(57) **CLAIM**

The ornamental design for a microfluidic cartridge, as shown and described.

DESCRIPTION

FIG. 1 is a front perspective view of a microfluidic cartridge showing a first embodiment of the new design;

FIG. 2 is a top plan view of the first embodiment of the cartridge shown in FIG. 1;

FIG. 3 is a front elevation view of the first embodiment of the cartridge shown in FIG. 1;

FIG. 4 is a rear elevation view of the first embodiment of the cartridge shown in FIG. 1;

FIG. 5 is a first side elevation view of the first embodiment of the cartridge shown in FIG. 1;

FIG. 6 is a second side elevation view of the first embodiment of the cartridge shown in FIG. 1;

FIG. 7 is a front perspective view of the second embodiment of the microfluidic cartridge of the new design; and,

FIG. 8 is a top plan view thereof, the front elevation, rear elevation, first and second side elevation views being identical to the respective views of the first embodiment, as shown respectively in FIGS. 3, 4, 5 and 6 herein.

The broken lines shown in FIGS. 1-8 are for illustrative purposes only and form no part of the claimed design.
